UNITED STATES PATENT OFFICE.

EDWARD A. WHITE, OF LEWISTON, IDAHO.

FRUIT-DRYING MACHINE AND METHOD.

Application filed January 27, 1928. Serial No. 249,979.

The object of this invention is to provide a novel means for drying fruit and the invention is especially addressed to the problem of drying whole fruit that has been wet by rinsing treatment.

The great desideratum of this invention is to not only provide means which will quickly perform the drying function, but also, to greatly shorten the machine in which such function is performed.

A further feature is to localize an intensive undivided air blast stream onto the fruit in such a manner as to drive off the water therefrom in the form of a light rain and hence the action is not one in which the relatively slow method of evaporation plays any part but it is essentially one in which force of impact of the air acts to break up and shatter the water globules and separate them from the fruit surface long before mere evaporation could function. In this phase, my invention also relates to the method, as well as the apparatus.

A further feature consists in facilitating the action of the air by presenting or exposing to the action of the latter the total peripheries of the fruit integers being dried.

It is a special feature of my invention to employ a fan as the source of supply of air since the volume of air required is so great, relatively speaking, that practically any other means for supplying air would be prohibited by high cost.

By reason of the fact that I depend very greatly not only on the high velocity with which the air is advanced, but also on the great volume of air, it will be appreciated that a very important feature of the invention consists in not only supplying the air in a single blast stream, but in freeing such blast stream not only from general changes of direction but from all other velocity impairing means such as perforated, foraminous, reticulated or like velocity impairment and interfering means. Thus, in accordance with my invention, the single blast stream advances in practically a total absence of any kind of interference until it contacts with the fruit.

It will now be clear that I can obtain an air velocity so great, merely with a fan as a source, that I can frictionally engage the fruit (impinged by the air stream) against the carrier with sufficient force to amount to a very considerable pressure.

The invention has many other features and

objects which will be more fully described in connection with the accompanying drawings and which will be more particularly pointed out in and by the appended claims. 60

In the drawings:

Fig. 1 is a sectional view on line 1—1 of Fig. 2, looking toward the left of the latter.

Fig. 2, is a sectional view on line 2—2 of Fig. 1, looking toward the right, and also 65 showing the polishing device in its operative relation to the drying mechanism.

Fig. 3, is a view of the polishing machine with the web in a different position from that shown in Fig. 2. 70

Fig. 4, is a face view of the polishing machine.

Fig. 5 is a fragmentary plan view of those rollers which are accelerated.

Like characters of reference designate similar parts throughout the different figures of the drawings. 75

In the specific form shown, I will first refer to the carrier, or broadly, the fruit supporting means, which, in this construction is in the form of a carrier. Said carrier, as shown, includes link chains 1, which are endless, and one bight of which is trained about a suitable wheel or wheels 2, mounted on a shaft 2', and power is applied in any suitable manner to 80 drive the chains so that the upper lap in Fig. 2, will travel toward the right thereof. Said carrier is preferably an open carrier and the same includes fruit supporting bars 3, which are preferably cylindrical, and which are rotatably journaled in the chains 1 and which project on opposite sides, or above and below said chains 1, as clearly shown in Fig. 2. Said bars 3, are transversely disposed with respect to the direction of travel of the carrier and are spaced apart from each other to carry the fruit in transversely disposed rows with the rows of fruit in spaced relation. The carrier is shown disposed substantially horizontally and I have shown means such as a slide 4, from which rows of wet fruit from the rinser can be delivered to the upper lap of the carrier in timed relation with the rate of travel of the latter. As the fruit is advanced toward the wheels 2', which point I will term the delivery bight, the rows of fruit are delivered by gravity onto a slide 5, to a polishing machine, which will later be described. From this point, the bars complete their endless circuit, as will be clearly 95 understood, the left hand bight not being

100 105 110

shown.

The function of this fruit supporting means or carrier is to support the fruit to be dried under or in the zone of action of an air blast, to be later described, and while the 5 fruit is within this zone of action, I provide means for facilitating the drying action by exposing all portions of the peripheries of the fruit to said blast.

This feature is herein specifically embodied 10 in the form of belts 6, one near each of the ends of the bars 3, these belts being trained about pulleys 7, mounted upon shafts 8, disposed in the manner shown. Power may be applied to one of the shanks 8, as by means 15 of a belt 9 and pulley 10. It will be noted that only the upper laps of belts 6 engage the lower end peripheries of bars 3, thereby leaving intermediate portions of said bars free and unobstructed for passage of air downwardly therebetween. Further, the belts 6, 20 are so relatively short that they only operatively engage a limited number of bars 3, of the upper lap of said carrier, as compared to the aggregate of said bars. In fact, it is the 25 function of said belts or means to only engage those bars 3 which are in the zone of the air blast. Said belts 6, are driven in the same direction as the carrier but at a greatly accelerated rate of speed with respect thereto. 30 Thus, those bars 3, which are engaged by belts 6, will be rotated in a contra-clockwise direction, as indicated by the arrows in Fig. 2, and at the same speed, so that there will be no tendency to pinch or injure the fruit on 35 said bars. Of course those bars 3, which are not engaged by belts 6, will not be rotated.

It may be informative to state that the rollers or bars 3, in actual practice, have been made two inches in diameter and spaced on 40 three inch centers so that the three rows of fruit being acted upon will occupy about six or eight inches, transversely of the rows. I have had highly efficient results by running the carrier at a rate of about six feet in twenty 45 seconds and running the belts 6, about six times the speed of the carrier.

Reference will next be made to my improved air blast means and the manner in which the latter coacts with the foregoing 50 mechanism.

The air blast means, as shown, consists of a single fan casing having a semi-cylindrical upper portion 11, which may be termed the 55 peripheral wall thereof. This wall, below a horizontal line intersecting the fan axis, is disposed with its lower portions 12, in parallel relation, thereby avoiding any air restriction. From points 13, I flare the walls as indicated at 14, in order to reach the sides of 60 the fruit on the carrier. I may, as shown, extend the walls downwardly, as indicated at 15, to localize the air action on the subjacent fruit. The side walls of the casing are indicated at 16 and 17 and they are shown 65 parallel down to points 18, from which they

slightly converge, as indicated at 19, toward the discharge end 20. I have shown the carrier charged with fruit about two and one half inches in diameter but of course I may desire to treat fruit that is at least five inches 70 in diameter and hence there is a sufficient clearance between the discharge end 20 and the carrier for such range of size. I preferably flange the walls 19, as indicated at 21, to act as guards tending to hold the air currents outside the main blast zone, toward the fruit. 75

Inside the fan casing, I have shown a fan 22, mounted on a shaft 23, journalled in bearings 24 and 25. A suitable source of power 80 may comprise an electric motor 26, directly driving shaft 23 and the fan thereon. In actual practice, I prefer to use the "Sirocco" type of fan (Davidson U. S. Patents, Re-issue, Nos. 12796 and 12797, issued May 26, 85 1908) because of its high efficiency, but I build the casing, as shown, and claim it as novel, in the combination set forth.

It will now be seen that I employ but a single fan and that the casing thereof, as shown, is disposed transversely of the travel of the carrier and that the flat walls are parallel with the rows of fruit travelling subjacent thereto. It will also be clear and this is important, that the discharge from the fan is entirely unobstructed, unrestricted and undivided by reason of absolute freedom of egress of the air. This is further emphasized by the fact that the discharge for the fan casing is in fact of greater cubical area than the main body of the fan. Thus, the air enters through the inlet openings 26', in wall 17, and is propelled directly downwardly against the fruit. With this type of casing, and a Sirocco fan therein, which latter is well known, I obtain a blast stream of from ten to fifteen thousand feet of air per minute, and I have propelled such fan by a five horse power electric motor. The fan casing discharge was three inches by twenty 100 four inches. In less than three seconds I can drive off all the water from a row of fruit. Therefore it will now be clear that in order to make a single fan perform the function that has otherwise taken a relatively 105 large apparatus, I have coordinated all the remainder of the apparatus into consonance with a single fan so that in a remarkably short time, and with a single undivided air current free from abutting or other interference, and with a surprisingly simple and compact mechanism, I can obtain a capacity that has heretofore been impossible.

It will readily be seen from Fig. 2, that the size of the single air blast stream is sufficient 110 to envelope the middle or central row of fruit entities.

In all apparatus heretofore known to me, the employment of either heated or cold air in drying whole fruit has inevitably been 115

Nov. 13, 1928.

to fully expose the fruit integers carried thereby.

7. In a fruit drying apparatus, an endless carrier having a relatively elongated fruit carrying bight or lap and provided with spaced rotatable cylindrical bars for supporting the fruit in spaced rows and said lap advancing at a slow speed, means for directing a blast of air on a limited number of rows of fruit as the latter are advancing, and short belts having laps running in the same direction as the lap of said carrier and at a greatly accelerated speed and engaging those bars in the zone of said blast for rotating said bars and causing the fruit integers thereon to rapidly turn and thereby expose all areas thereof to said blast.

8. In a fruit drying apparatus, an open carrier for continuously and slowly advancing fruit thereon, an air blast means directed onto a portion of the fruit on said carrier and of sufficient velocity to drive the water off from said fruit and also from off that portion of the carrier beneath said blast in the form of rain, and means for causing that portion of the fruit under said blast to rapidly turn to expose all portions of such fruit to said blast in addition to the fruit changing position effected by advancing movement of said carrier.

9. In a fruit drying apparatus, a carrier having bars supporting fruit in rows disposed transversely to the direction of travel of said carrier, a rotary fan having a casing disposed above said carrier and said casing having a single discharge end opening in superposed relation above a limited number of

rows of fruit and said discharge end leading straight from said casing and being of such greater cross section than the latter as to afford unrestricted passage of air therethrough directly onto that portion of the fruit immediately subjacent said discharge end.

10. The herein-described method of drying whole fruit, which consists, in turning dripping wet fruit to expose all surface areas thereof, and in directing onto said turning fruit an undivided air blast stream free from interference and of a size to envelope fruit entities and of sufficient velocity to physically drive off the water like rain before evaporation of the water can take place.

11. The herein-described method of removing water from whole fruit, which consists, in rapidly turning and slowly advancing dripping wet fruit, and in directing onto said turning and advancing fruit an air blast stream free from interference and of sufficient velocity to physically envelope and drive off the water from said fruit before evaporation of the water can take place.

12. In a mechanism for removing water from whole fruit, means for rapidly turning dripping wet fruit to expose all surface areas thereof, and means for blowing an undivided stream of air against said turning fruit of a size to envelope fruit entities and with a sufficient velocity to physically drive off the water from said fruit before evaporation of the water can take place.

In witness whereof, I hereby affix my signature.

EDWARD A. WHITE.
